UNITED STATES PATENT OFFICE.

GEORGE WILFRED WRIGHT, OF ELIZABETH, NEW JERSEY.

DESK-REMINDER.

1,006,334.

Specification of Letters Patent. Patented Oct. 17, 1911.

Application filed March 18, 1911. Serial No. 615,249.

To all whom it may concern:

Be it known that I, GEORGE WILFRED WRIGHT, a citizen of the United States, and a resident of Elizabeth, in the county of Union and State of New Jersey, have invented 5 a new and Improved Desk-Reminder, of which the following is a full, clear, and exact description.

This invention relates to a new and improved 10 device adapted to be set on a desk or table for the purpose of holding memorandum tabs or sheets of paper, to remind the user of some points which he desires to remember.

15 An object of this invention is to provide a device which will hold a plurality of memorandum tabs in separate readily-accessible positions, whereby they can not only be readily removed and inserted, but also can 20 be at least partially visible, so as to be distinguishable one from the other.

A further object of this invention is to provide a desk-reminder which will be simple in construction, inexpensive to manufacture, strong, durable, capable of being made 25 of any suitable material, such as sheet-metal, and affording sufficient surface to apply advertising matter, so that if desired, the same can be given away as an advertisement.

30 These and further objects, together with the construction and combination of parts, will be more fully described hereinafter and particularly set forth in the claims.

Reference is to be had to the accompanying 35 drawings forming a part of this specification, in which similar characters of reference indicate corresponding parts in all the views, and in which—

Figure 1 is a perspective view; Fig. 2 is a 40 vertical section on the line 2—2 of Fig. 1; and Fig. 3 illustrates the blank from which the device is formed.

Referring more particularly to the separate parts of this invention as embodied in 45 the form shown in the drawings, it will be seen that there is provided a base 1, from which extends upwardly, preferably at an acute angle thereto, a riser 2, so as to form a reclining support. This support is pro-

50 vided with a plurality of holders 3, between which and the support may be inserted sheets of paper or other tabs on which memoranda may be placed. They may also hold anything which it is desired to attract the at-

55 tention of the user to at some future time.

In the form shown in the drawings, these holders are formed by providing U-shaped slots or cuts 4 in the riser, and stamping the tongue thus formed slightly outward, with the greatest extent of offset from the body 60 of the support located at the top, so that the memorandum tabs can be readily inserted between the tongue and the support.

Secured to the base, there is provided a handle 5, which also forms a base on which advertising matter can be readily stamped or printed, so that it will be in a position to attract the attention of the user and other parties coming in juxtaposition thereto. It will be seen that the handle or advertising strip 5 is formed by cutting a somewhat ovate slot or incision 6 in the blank, and then bending it up at right-angles to the base, leaving a short neck portion at 7, where the handle is connected to 70 the base. It is further to be seen that the base 1 and the riser 2 are formed integral with each other, that is to say, all of the members of the device are stamped from a single strip of metal having an elongated 75 portion at one end, which forms the riser, and an enlarged portion at the other end, from which the handle and the base are constructed.

The utility of the device will be readily 80 understood when taken in connection with the above description. The device is set on the desk or any other readily accessible position, where the user can readily see any 85 memory tabs which he may secure thereto 90 by means of the holders 3. These tabs, by virtue of the spaced relation of the holders, are separable one from the other, and in fact, separately visible, so as to be readily 95 distinguished one from the other. The handle 5 forms a sufficient surface on which an advertisement may be stamped, so that, if desired, the device can be given away as an attractive and useful advertisement, which 100 will always be before the eyes of the user. The fact of the device being made from a single sheet of metal permits it to be manufactured at a trifling expense, and yet does not detract from its usefulness.

While I have shown one embodiment of 105 my invention, I do not wish to be limited to the specific details thereof, but desire to be protected in various changes, alterations and modifications which may come within the scope of the appended claims. 110

Having thus described my invention, I claim as new and desire to secure by Letters Patent:—

1. The combination with a base, of a riser connected to said base, said riser having a plurality of U-shaped slots cut therein, forming tongues, said tongues being stamped from the body of said riser to form holders adapted to secure between themselves and said riser, memory tabs, and a handle stamped out of said base, and bent at an angle to said base and said riser.

2. A desk reminder, comprising a base, a riser, and a handle, said desk reminder being formed of a single integral sheet of material having an elongated portion and a transversely-enlarged portion, integral with each other, said elongated portion having U-shaped cuts therein forming tongues, said

tongues being bent out from the body of said elongated portion to form holders spaced apart at their upper ends from said riser, said base and said handle being formed from said enlarged portion, said handle being bent at substantially right-angles to said base, and said elongated portion being bent at an acute angle to said base to form said riser, which extends in a reclining position when said base assumes a horizontal position.

In testimony whereof I have signed my name to this specification in the presence of two subscribing witnesses.

GEORGE WILFRED WRIGHT.
